UNITED STATES PATENT OFFICE.

SVEN J. STRID, OF CHICAGO, ILLINOIS, ASSIGNOR TO FRED MATHEWS, OF CHICAGO, ILLINOIS.

SAFETY DEVICE FOR BRAKE-LEVER SPREADERS.

Application filed September 30, 1926. Serial No. 138,785.

This invention relates to the art of railway brake equipment, and has reference more particularly to an improved safety device for the rod or bar that connects the lower ends of the two brake levers on a truck and underlies the spring plank, and is commonly known as the brake lever spreader.

Heretofore, so far as I am aware, the safety device for this purpose has consisted of a generally U-shaped hanger riveted or bolted to the spring plank and depending from the latter, through which the spreader extends so that, in the event that the spreader accidentally becomes disengaged from the lower end of either lever it will be caught by the safety device and prevented from dropping onto the track.

The object of the present invention is to provide a simple, inexpensive and highly efficient safety device which may be easily and quickly and permanently connected to the spring plank without requiring the use of extraneous fastening devices.

My invention, in several practical forms in which it may be embodied, is illustrated in the accompanying drawing, in which—

Fig. 1 is an elevation of a portion of the brake lever spreader with the spring plank in transverse section, and my improved safety device applied thereto;

Fig. 2 is an end elevation;

Fig. 3 is a view similar to Fig. 2, omitting the spreader and lever, showing another form of the invention;

Fig. 4 is a vertical section on the line 4—4 of Fig. 3;

Fig. 5 is a view similar to Figs. 2 and 3 showing still another form of the invention;

Fig. 6 is a vertical section on the line 6—6 of Fig. 5.

Referring to the drawing, and describing first the form of the invention shown in Figs. 1 and 2, 10 designates the usual spring plank of a railway truck, 11 designates the brake levers, and 12 designates the brake lever spreader consisting of a rod or bar underlying the spring plank 10 and articulated at its ends to the lower ends of the brake levers 11.

13 designates each of a pair of U-shaped hangers bent to form from a rod section. In applying these hangers to the spring plank, a pair of holes 14 are drilled or otherwise

formed in the side flanges of the latter, and through these holes the offset upper end portions 15 of the hanger arms are inserted. Then the ends of the offset portions are hammered down over the upper edges of the flanges of the spring plank from the position indicated in dotted lines to that shown in full lines. The offsets thus form shoulders 16 and hook 17 which securely but removably hold the hangers in position.

In the form of the invention illustrated in Figs. 3 and 4, each U-shaped hanger 18 is bent to form from a section of strap iron or malleable steel, and the upper portions 19 of the limbs thereof are twisted, through a right angle, forming shoulders 20, and are inserted through slots formed in the bottom wall of the spring plank adjacent to the flanges thereof, extending upwardly along the inner surface of the side wall, the extreme upper portion of each limb being then hammered down over the upper edge of the side wall, from the position shown in dotted lines to that shown in full lines, forming hooks 21.

In the form of the invention illustrated in Figs. 5 and 6, the hanger 22 is bent to form from a section of strap iron, and the standing limbs 23 and 24 thereof are twisted or warped through a right angle forming shoulders 25, and the limb 23 is extended up across the outer side of the side wall of the spring plank with its upper end portion bent down over the upper edge of said wall to form a hook 26, while the offset upper end 27 of the other limb is extended through a slot 28 formed in the corner portion of the spring plank and engages the upper face of the bottom wall of the spring plank.

In all cases the brake lever spreader 12 extends through the pair of hangers, as shown in Figs. 1 and 2, said hangers serving to catch and sustain the spreader bar against dropping to the track in the event of accidental disconnection from the brake beam at either end.

The main advantage of my invention, as compared with safety devices for the same purpose heretofore used, is that it entirely obviates the use of rivets, bolts or other fastening devices, and hence is cheaper, easier and quicker to apply, and fully as permanent and reliable in the performance of its function as the riveted or bolted hangers heretofore used.

In all of the forms shown the hooks and shoulders of the limbs of the hangers so engage the spring plank that it is impossible for the hangers to jar loose.

5 I claim—

1. The combination with an apertured spring plank, of a brake lever spreader safety device consisting of a hanger through which the spreader extends, said hanger having an attaching portion thereof passed through the aperture of said spring plank and bent into interlocking position with relation thereto.
- 10 2. The combination with an apertured spring plank, of a brake lever spreader safety device consisting of a U-shaped

hanger through which the spreader extends, said hanger having its arms passed through the apertures of said spring plank and bent into interlocking position with relation 20 thereto.

3. The combination with an apertured spring plank of U-form in cross-section, of a brake lever spreader safety device consisting of a U-shaped hanger through which 25 the spreader extends, said hanger having its arms passed through the apertures of said spring plank and at their upper ends bent over the upper edges of the side walls thereof.

SVEN J. STRID.
